UNITED STATES PATENT OFFICE.

PATRICK MC GUIRE, OF KEEWATIN, MINNESOTA.

COLLAPSIBLE FORM FOR FORMING CIRCULAR CONCRETE STRUCTURES.

1,182,578.

Specification of Letters Patent.

Patented May 9, 1916.

Application filed January 7, 1915. Serial No. 981.

To all whom it may concern:

Be it known that I, PATRICK MC GUIRE, a citizen of the United States, residing at Keewatin, in the county of Itasca and State of Minnesota, have invented certain new and useful Improvements in Collapsible Forms for Forming Circular Concrete Structures, of which the following is a specification, reference being had therein to the accompanying drawing.

10 My invention relates to improvements in collapsible forms for forming circular concrete structures.

The object of my invention is to provide a form of this character which would be readily set up and collapsed, and is especially designed to be used in building of cylindrical structures such as smoke stacks, water tanks, silos or the like.

20 Another object of my invention is to provide a collapsible form of this character which is simple in construction and one that will retain perfect alinement both vertically and horizontally and having certain details 25 of structure and operation hereinafter more fully set forth.

In the accompanying drawings:—Figure 1 is a side elevation of one of the staves of which my improved form is made and showing interlocking members. Fig. 2 is a side elevation of one of the staves used for forming the inner wall of the form. Fig. 3 is an edge view of Fig. 1. Fig. 4 is an end view of Fig. 2. Fig. 5 is a side elevation of the 35 improved cable tightening turn-buckle. Fig. 6 is a top plan view of Fig. 5. Fig. 7 is a bottom plan view of Fig. 5. Fig. 8 is a perspective view of a group of staves in position as used to form the inside of the concrete structure showing the securing bands 40 in their proper positions. Fig. 9 is a perspective view similar to Fig. 8 of a group of staves assembled to form the outer structure, with the inclosing cables in position.

45 Referring now to the drawings, 1 represents a wooden stave which, taken together with other staves, form the outside of the mold for molding the concrete circular structure. The edges of the wooden staves 50 are slightly beveled for the purpose of forming the outer wall of a circular form. It is understood that any number of these staves may be employed for this purpose, the number used being determined by the size of the 55 circular structure to be constructed. These staves are of any desired length, but pref-

erably of such a length that they can be readily handled.

Attached to the upper end of the wooden staves are the metallic cap portions 4 which snugly fit the upper edge of the staves flush 60 with the upper end and secured thereto by means of screws or in any other suitable manner. These caps 4 are provided on their outer edges with the downwardly extending 65 portions 2 which are formed integral therewith. The upper ends of the caps are provided with knobs 5 designed to be of such a size as to interlock with a recess formed of the stave above as will be later described. 70 The portion 2 is adapted to closely fit the outside of the upper end of the stave 1 and has a lug portion 7 integral therewith and provided with a groove or slot 8 into which the tightening or holding cables hereinafter 75 more fully described pass.

At one side of the portion 6 of the attachment 2 is an outwardly extending male portion 9 which extends beyond the edge of the stave a distance suitable for interlocking with the female recess 10 of the adjoining stave. The lower end of the stave is provided with an attachment 11 somewhat similar to the attachment 2 carried by the upper end of the stave and provided with a 80 U-shaped portion 12 fitting closely with the lower end of the stave and provided with projecting flanges extending downwardly sufficiently to contain the knobs 5 carried by the upper end of the staves below. The 85 attachment 11 is also provided with the lugs 13 having the grooves 14 therein for receiving the securing cable passing around the form. The attachment 11 is also provided with a male portion 15 and female portion 95 16 forming the interlocking means. The male portion 15 extends outwardly beyond the edge of the stave and is adapted to enter the female portion 16 of the adjoining stave as clearly shown in Fig. 9 of the drawings. The attachments 2 and 11 are secured 100 to the ends of the staves by means of the screws 3 and 16' as fully shown in Figs. 3 and 4 of the drawings. The male portions 9 and 15, carried by the stave 1 are sufficiently 105 flexible to accommodate themselves to the curve which they must take on the outer wall of the form as clearly shown in Fig. 9 of the drawing. The inner staves forming the inner form designated by the reference 110 numeral 1' are constructed the same as that shown in Fig. 1 of the drawings only they

have their edges beveled in the opposite direction so as to assume the reverse curve as that formed by the stave 1 and whereby they are held together from inward movement. 5 The attachment 11 is exactly the same as that shown on the outer stave except that the groove 14 is not formed therein. The upper member 2 is like that shown in Fig. 1 of the drawings, but is provided with an outwardly 10 extending lug 33 which is for the purpose hereinafter more fully described.

It will be readily seen that the series of staves equipped in the form shown in Fig. 1 of the drawings when placed side by side 15 and slightly beveled and having the members 9, 10, 15 and 16 interlocked, will form a continuous circular form about the outside of a given circular space and be self sustained. It may be also seen that another 20 similar series are mounted upon the first and interlocked therewith by means of the U-shaped portions 12 of the attachment 11 of the upper series and the knobs 5 of the lower series. Additional interlocking effect 25 along the edges of the staves may be had by tongue-and grooving thereon, not shown on the drawings. In addition in order to form a more perfect union of the staves, I provide cables 17 and 17' passing 30 through the grooves 8 and 14 holding the several staves together to form the outer wall of the circular form. As a means of tightening these cables, I provide a turn-buckle attachment shown in Fig. 5 of the 35 drawings which is of such a length less than that of the staves as to bring the cables in alignment with the recesses 8 and 14 in the plates 2 and 11 carried by the staves. The turn-buckle consists of a frame 18 terminating 40 at its extremities in the blocks 19 and 20. These blocks may be of either wood or metal or may be formed integral therewith. Screws 21 and 22 are mounted therein which 45 terminate at their upper ends in the square portions 23 and 24 respectively. These squared portions serve as means for rotating the screws whereby the cables are tightened as will be later described. Mounted 50 upon the screws or worms 21 and 22 are the nuts 25 and 26 respectively which are provided with grooves suitable for the passing 55 around of the cables. The blocks 19 and 20 are pierced by holes 27 and 28 at a point approximately at the center thereof and through which one end of the cables 17 60 is passed and firmly secured. Grooves 29 and 30 are provided with the blocks 19 and 20 for the passing of the cables therethrough, it being the design to pass the 65 cables in this point through the entire series of the staves by means of the grooves 8 and 14 thence they will return to the turn-buckle from the opposite direction. This is for the purpose of providing grooved portions 31 and 32 for the return of the cable,

it being designed to pass the free end about the nuts 25 and 26 within grooves therein and to attach said free end thereto by means of loops as shown in Fig. 5 of the drawing. It will be seen from the above that by turning the screws or worms 21 and 23, the nuts 25 and 26 will travel up and down as the case may be, thus drawing upon the cable 17 and therefore tightening them about the circular series of staves and locking them in their circular form. By this structure it will be seen that a rigid cylinder is formed presenting a smooth, unbroken inner surface which is most desirable for the forming of an outer wall for a concrete structure 70 of this nature. It will also be seen that a reversal of the above operation would cause the cables to slacken which would allow for the disassembling of the several staves forming the outside form for the concrete 75 structure.

The means for supporting the inner wall of the cylinder structure in suitable position, with the staves 1' hereinafter referred to, are used and set up one alongside the other with the interlocking members 9, 15, 10 and 16 in their interlocked position. These staves are also provided with knobs 5 mounted upon similar attachments as that shown in Fig. 1 which provides for the building up of the staves one upon the other. These staves, of course, are slightly beveled, but in an opposite direction to that of the stave 1 in order that the curve formed thereby may be the reverse of that formed by the outer staves. These staves are also provided with the male and female portions 9 and 10, 15 and 16, but the lugs 7 and 13 and grooves 8 and 14 are omitted on these staves. In place of the lugs 8, I provide the single hooked portion 33 formed integral with the attachment 2. This hooked portion is designed to have the band 34 pass around the inner staves under the hook to retain the inner wall in its proper position and also to reinforce the same against the pressure of the concrete between the forms. It will be seen from the foregoing that a series of these inner staves placed side by side and interlocked by means of their male and female interlocking portions 9 and 10, 15, and 16, will form a continuous circular wall about any given circular space and successive series of the same may be erected; one above the other and interlocking with each other to form the inner wall of the mold for forming the concrete structure. It is also understood that these forms may be adapted to form tapering circular structures such as smoke-stacks, and the like, and this is accomplished by having the staves slightly tapering toward their upper ends which would provide for the taper of the concrete structure.

Having thus fully described my invention,

tion what I claim and desire to secure by Letters Patent is:

1. A device of the character described comprising a stave, metal caps fixed upon the ends of the stave, a longitudinal projection upon the cap upon one end of the stave and a groove in the cap upon the opposite end whereby a series of staves may be assembled abutting each other and held in alinement by the coöperating projections and grooves.

2. A stave for collapsible forms having fixed upon one end a metal cap having an upwardly projecting knob and a downwardly extending portion carrying a laterally extending male member, a female member and a binder receiving lug, a metal cap fixed to the opposite end of the stave and leaving a downwardly projecting groove, an upwardly projecting portion carrying a laterally extending male member, a female member and a binder receiving lug, as for the purpose described.

3. A device of the character described, comprising elongated wooden staves having metal caps covering the ends thereof, said caps each having an arm and socket for coöperation with the next adjacent caps, the lower cap having a socket in its lower face and the upper cap having a projection on its upper face whereby series of staves are adapted to be set one upon the other and adjustably held in alinement.

4. In a device of the character described, elongated wooden staves having metal caps covering the ends thereof, said caps each having male and female members for coöperation with the next adjacent similarly equipped stave.

5. In a device of the character described, elongated wooden staves having metal caps covering the ends thereof, said caps each having male and female members for interlocking coöperation with the next laterally adjacent similarly equipped staves and male and female coöperating members for en-

gagement with the next vertically adjacent similarly equipped staves.

6. A stave for making concrete structures provided with metal caps covering the ends 50 and extending down one side thereof, the tops of the upper and lower caps provided with studs and grooves respectively, the side portions provided with a laterally extending member and a recess opposite thereto, 55 the said laterally extending member adapted to snugly fit within the recess of the cap of the adjacent stave and locking the said stave against vertical movement and means engaging the extension of the caps of the 60 said staves for holding them against lateral movement.

7. A stave for making concrete structures provided with caps on the ends thereof, 65 means carried by the caps for uniting the staves and holding them against vertical movement and means engaging the face of the said staves for holding them against lateral movement.

8. A stave for making concrete structures 70 comprising a wooden member provided with metal caps on each end thereof, means carried by the caps for uniting the staves and holding them against vertical movement, the said means comprising snugly fitting 75 male and female members and means engaging the said caps for holding the staves against lateral movement.

9. A stave for making concrete structures comprising a wooden body portion provided 80 with metal caps on each end thereof, means carried by the caps for uniting the staves and holding them against vertical movement, and means engaging the said caps for holding the staves against lateral move- 85 ment.

In testimony whereof I hereunto affix my signature in the presence of two witnesses.

PATRICK MCGUIRE.
